AMUSEMENT RIDE

John N. Bartlett, Cleveland, Ohio

Application July 6, 1932, Serial No. 621,037

14 Claims. (Cl. 104—84)

This invention relates to improvements in amusement rides, and more particularly relates to an amusement ride over which passengers are adapted to be carried and in connection with which various illusion devices are employed to create the impression of riding in an airplane.

One object is to effect the sensation of a banking turn in an airplane by rocking the ceiling and side walls of a closure into which a car is driven.

Another object is the accomplishment of an illusion of rolling by a novel method including revolving ultra violet light beams projected on the interior surface of a horizontally disposed, cylindrical closure having said interior surface coated with stripes of luminescent paint.

A further object of this invention is to create the illusion of spinning by projecting rotating beams of ultra violet light on the interior surface of a vertically disposed closure adapted to receive an amusement car.

With these and other incidental objects in view, the invention consists of certain novel features of construction and combinations of parts, the essential elements of which are set forth in the appended claims and a preferred form or embodiment of which is hereinafter described with reference to the drawings which accompany and form a part of this specification.

In said drawings:

Fig. 1 is a sectional view through the barrel roll illusion tunnel.

Fig. 2 is a fragmentary view through the barrel roll illusion tunnel.

Fig. 3 is a sectional view taken through the blanking illusion tunnel.

Fig. 4 is a sectional view through the light cylinder for the barrel roll illusion device.

Fig. 5 illustrates a modified form of light projecting means for the barrel roll illusion.

Fig. 6 is a vertical sectional view through the spinning illusion tunnel.

Fig. 7 is a horizontal sectional view through the spinning illusion building.

Fig. 8 illustrates another modified form of light projecting means for the barrel roll illusion.

General description

The amusement ride forming the subject matter of the instant application has for its main purpose the creating of the various illusions appertaining to an airplane ride, such, as the spin, barrel roll, side slip, banking and the illusion of speed. It is to be borne in mind that the cars in which the passengers are carried travel at a constant, moderate speed, excepting when on an

incline, at which time an over-running clutch in the drive wheel permits the car to accelerate, due to the force of gravity.

I provide means temporarily to arrest movement of the cars in the tunnel-like structures wherein the several illusions are produced. After a brief interval in each tunnel the car automatically proceeds to the next feature where its motion is again arrested for a brief period of time.

The cars are designed to simulate low winged monoplanes and are capable of turning in a very short radius. This is due to the novel method of mounting the front end of the car on two caster wheels and mounting the rear end of the said car on a single large drive wheel.

The illusions of speed, spinning and rolling are created by simple lighting effects and revolving light beams of ultra violet rays or the equivalent. These revolving rays or beams are projected onto the interior walls of the tunnels which walls are covered with spiral stripes of a luminescent substance such as paint. By reversing the direction of rotation of the light beams the physical sensation of a reversal of the illusion is obtained.

Barrel roll illusion

The car 31 enters a cylindrical barrel roll illusion tunnel 130 over the guide rail 43 after passing over the switch 34. As the car enters the tunnel the drive wheel 120 engages and closes a treadle switch 129 (Fig. 1) to supply current to the illusion producing devices. These include a rotating cylinder 131 having spaced longitudinal slots 132 (see Fig. 4) therein through which slots horizontal beams of light are projected from a light source located within the cylinder. The light source 133 may produce either near ultra violet rays, neon red or other suitable light beams. The light source 133 is suitably supported within the cylinder but does not rotate therewith, merely projecting its rays through the slots in the rotating cylinder 131.

The interior wall of the tunnel 130 is painted or sprayed with a flat black, spiral stripes being painted thereon with fluorescent paint substantially as illustrated in Figure 2. The horizontal light beams disclose to the passengers in the car, squares of light between which light squares are dark or black squares. These light and dark squares or patches, as the cylinder 131 rotates, carry the eye around and forwardly depending upon the pitch of the stripes and the speed and direction of rotation of the cylinder, thus creating the illusion that the car is rolling over and

over and that it is proceeding forwardly at increased speed.

A light shield 134 (Fig. 1) extending the entire length of the light cylinder 131 is carried on a 5 supporting frame 135 mounted on the track frame 136 to prevent the light beams from reaching the passengers, the car or the track.

A motor 137 (Figs. 1 and 2) is provided to rotate the light cylinder 131. This motor is suitably mounted on the top of the tunnel 130 and drives the cylinder 131 by a shaft 138 and beveled gears 139 and 140.

As the car enters the tunnel 130 and strikes the treadle switch 129 it also supplies current to 15 a motor driven eccentric 141 connected to the track frame 136 by a rod 142. The track frame 136, mounted on rollers 143, is oscillated as the eccentric 141 is operated, thus accentuating the effect of the illusion.

20 A modified form of the device for projecting the patches or squares of light onto the interior walls of the tunnel 130 is illustrated in Figure 16. This device includes a rotating cylinder 144 having a plurality of small mirrors 145 supported on radially extending arms 146 of various lengths. The light source 300 (Fig. 5) in this case is located at one end of the cylinder 144 and is projected longitudinally along the periphery of the cylinder where the rays of light are caught at intervals by the mirrors 145 and reflected in 25 the shape of small patches onto the interior walls of the tunnel 130, which walls, in this case, are covered entirely with fluorescent paint.

30 Another modified form of the device for projecting patches of light onto the interior walls of the tunnel 130 (Fig. 2) is illustrated in Figure 8. This embodiment of the device has for its purpose the projection of the light patches onto the interior walls of the tunnel from the exterior 35 thereof. By that it is meant to locate the entire projecting means as well as the light source on the outside of the tunnel structure thus leaving the interior of the tunnel clear of any obstructions.

40 In this case a truncated cone 155 (Fig. 8) is mounted on and secured to a shaft 156 rotatably mounted in brackets 157 secured to the end wall of the tunnel structure 130. A gear 158 secured to the end of the shaft 156 meshes with the gear 50 139 previously described, which gear 139 is fast on the lower end of the vertical shaft 138.

45 The rays of light, projected from a suitable projector 159 strikes mirrors 207 mounted on stems 208 projecting from the cone 155 and are reflected at various angles onto the interior walls of the tunnel 130. As the cone 155 is rotated by the motor 137 (Fig. 2), as set forth above, the light rays are caught at intervals by the mirrors 207 and projected onto the walls of the tunnel 60 130 in the shapes of small patches of light. These patches of light traveling or rotating about the walls, which are completely covered with fluorescent paint, create the illusion of rolling.

65 The object of using this form of projecting means outside of the tunnel is that by so doing the entire height of the interior of the tunnel is clear and, instead of patrons riding thru the tunnel in cars as described above, they may 70 walk into the tunnel and receive the same illusion of rolling.

75 After remaining for a predetermined interval of time in the tunnel the car leaves through suitable swinging doors (not shown) and after traveling along a section of guide rail, the length

of which may be varied to suit conditions, said car enters a spinning illusion device.

The spinning illusion

The device for producing the spinning illusion 5 includes a vertically disposed, cylindrical building 147, to which entrance is gained through swinging doors 148 (Figs. 6 and 7). The building 147 is constructed substantially in the same manner as the tunnel 130 for the barrel roll illusion, the chief difference being that the tunnel 130 is in a horizontal position whereas the building 147 is in a vertical position. A rotating cylinder 149 is suspended from a bracket 150 secured to the ceiling of the building 147, the bracket 15 also acting as a support for a driving motor 151 for the light cylinder 149. Current is supplied to the lamp within the cylinder 149 by the usual slip rings 152. The cylinder 149 has longitudinal slots therein to project vertical beams of near 20 ultraviolet light or other suitable light onto the luminescent stripes on the interior wall of the building 147. Suitable light screens 153 are provided at the top and bottom of the cylinder 149 to prevent the projected beams of light from 25 striking the ceiling and floor of the building.

As the car enters the building through the 30 swinging doors 148 it runs onto a section 154 of the guide rail. This section normally is disconnected from the electrical circuit and consequently, when the current pick-up device engages this section of the rail, the motor ceases to drive the car and the wing of the car, engaging a spring pressed drag brake 160, brings the car to a stop at a point substantially in the 35 center of the building. In this position of the car the rear wheel 120 rests on a section 161 of the floor, said section being mounted on rollers to permit lateral movement. A suitable motor 162 is provided to reciprocate the section 161 thus imparting a swaying movement to the rear end of the car to heighten the effect of the illusion.

Shortly after the car enters the building 147 the wing opposite the wing which engages the 40 drag brake 160 comes into contact with a switch operating bar 163 carried at the upper ends of a series of arms 164, pivotally mounted as at 165. Springs 166 normally urge the brake bar 163 toward the car. As the wing of the car 45 comes into contact with the bar 163 said bar and the arms 164 upon which it is carried are rocked counter clockwise as viewed in Figure 20, pressing a plunger 167 which in turn operates a switch 168. This switch is mounted on 50 a bracket 169 secured to the floor and is normally open but when operated as just described, supplies current to the various illusion creating devices including the light source in the cylinder 149, the motor 151 for the rotating cylinder, 55 and the motor 162 for oscillating the floor section 161.

The switch 168 also controls the supply of 60 electrical current to sound producing devices to simulate the sound of wind in the wires of an 65 airplane. The switch 168 normally interrupts the flow of current to a suitable delay switch 170 which, after a predetermined interval of time, during which the illusion of spinning is effected, supplies current to the section 154 of the 70 guide rail. The drive motor immediately starts the car which leaves the building through swinging doors 171. As the wing of the car is disengaged from the switch bar 163 the spring 166 rocks the arms 164 clockwise carrying the 75

bar 163 away from the switch 168 thereby opening the electrical circuit to all of the illusion producing devices which operate in connection with the spinning illusion.

5   *Mechanical illusions*

Mechanism is provided to convey the illusion or simulation of what is known in aviation as "banking". This illusion is effected by pivotally supporting a section of the track to permit sidewise swaying motion and at the same time rocking the ceiling and raising and lowering the side walls of a structure enclosing the pivotally mounted section of track.

10   A section 191 (Fig. 3) of the track, pivotally supported at 192 by a bracket 193, is connected to a motor driven eccentric 194 by a link 195 so that operation of the eccentric rocks the track section 191. A link 196 connects the eccentric 15 194 to an arm of a lever 197 supported by a bracket 198. A link 199 connects the other arm of the lever 197 to one of a pair of side walls 200, one pivotally supported at each end of a rocking false ceiling 201, which ceiling is 20 25 pivotally supported by a bracket 202 suspended from the true ceiling 203 of the building.

Inspection of Figure 3 discloses that operation of the eccentric 194 will rock the track section 191 clockwise and at the same time lower the 30 left hand wall 200, rock the false ceiling 201 counter clockwise and raise the right hand wall 200. The walls 200 are guided in their vertical reciprocating movement by projections 205 embracing brackets 206.

35   Each of the side walls 200 are painted with luminescent paint. Onto these walls horizontal bars of light are projected through slots in shields 210 covering lights 211 set in recesses in the false ceiling 201. As the ceiling 201 is 40 rocked, as above described, raising and lowering the side walls 210 the bars of light emanating from the lights 211 move over the side walls in the same direction the walls are moving but at a higher rate of speed, thus in conjunction 45 with the rocking track section 191 creating the illusion of banking.

Obviously a similar illusion could be produced by rocking the light cylinder 131 (Fig. 2) instead of rotating it.

50   As the car enters the banking illusion building it strikes a conveniently located switch (not shown) which closes the electrical circuit to the motor 194. The motor immediately commences 55 rocking the track 191 and the false ceiling 201 in opposite directions. Current is also supplied by the switch (not shown) to the lamps 211 set in the recesses in the false ceiling 201 and adapted to rock therewith. The lamps 211 produce near ultra violet light or similar light which 60 is projected onto the side walls 200. These rays of light, moving in the same directions with the rising and falling side walls 200 add materially to the illusion of banking.

The car traveling slowly ahead on the swaying track 191 while the walls 200 and the ceiling 201 move in opposite directions with the dimly lighted bars of light projected onto the walls by the lights 211 creates a very effective sensation of banking.

70   While the forms of mechanism herein shown and described are admirably adapted to fulfill the objects primarily stated it is to be understood that it is not intended to confine the invention to the one form or embodiment herein disclosed, for it is susceptible of embodiment in

various forms all coming within the scope of the claims which follow.

What is claimed is:

1. In an amusement device of the class described, the combination of a stationary member 5 having fluorescent configurations arranged in continuous spiral stripes, an ultra-violet light source, a light directing means surrounding said light source to direct a plurality of beams of light onto said configurations, each beam extending the length of the member, and means to rotate the light directing means.

2. In an amusement device of the class described, the combination of a stationary cylindrical member having fluorescent configurations 15 arranged in spiral stripes, an ultra-violet light source, a cylindrical light directing means surrounding the light source, said light directing means being parallel to the axis of and substantially the same length as the cylindrical member 20 to project light beams onto the configurations, and means to rotate the light directing means.

3. In an amusement device of the class described, the combination of a stationary cylindrical member having continuous fluorescent configurations, an ultra-violet light source, a cylindrical light directing means surrounding said light source to project a plurality of bands of light onto said configurations, each band illuminating 25 a narrow portion of the cylindrical member 30 throughout the length of said member, and means to rotate the light directing means.

4. In an amusement device of the class described, the combination of a stationary cylindrical member having continuous fluorescent configurations, 35 an ultra-violet light source, a light directing means surrounding the light source and having a plurality of longitudinal slots therein extending substantially the length of the directing means to direct light beams onto the configurations, and means to rotate the light directing means.

5. In an amusement device of the class described, the combination of a stationary member having continuous fluorescent configurations, 45 an ultra-violet light source, a cylinder surrounding the light source said cylinder having longitudinal slots in its periphery extending parallel with and substantially the length of the cylinder to direct light onto the configurations, and means 50 to rotate the cylinder.

6. In an amusement ride of the class described, the combination of a closure having its inner walls covered with fluorescent material, a car adapted to be driven into said closure, a rotatable member, a normally deenergized light source adapted to project a beam of light longitudinally of the rotatable member, a plurality of reflecting means carried by said rotatable member to reflect beams of light onto the inner walls of the closure, normally deenergized means to rotate the rotatable member, and a switch adapted to be closed by the car simultaneously to energize the light source and the rotatable means.

7. In an amusement device of the class described, the combination of a closure having its inner walls covered with fluorescent material, a light producing means located externally to said closure, a light directing means located externally to said closure, and means to rotate the light directing means to create an illusion of physical movement of riding in an aeroplane.

8. In an amusement device of the class described, the combination of a closure having its inner walls covered with fluorescent material, a 75

- 5 light projecting means located externally to said closure, a conical member adapted to be rotated externally to said closure, a plurality of mirrors on said member, said mirrors being adapted to reflect the projected light onto the interior walls of the closure to create the illusion of physical movement of riding in an aeroplane.
- 10 9. In an amusement device, the combination of a room having its walls covered with fluorescent substance, means to project a plurality of parallel beams of ultra-violet light onto said walls, and means to rotate the projecting means.
- 15 10. In an amusement device, the combination of a room having its inner walls covered with fluorescent substance, an ultra-violet light source, and means to project a plurality of parallel beams of light from said source onto the walls and to cause said beams to travel about the walls.
- 20 11. In an amusement device the combination of a room having its inner walls covered with fluorescent substance, an ultra-violet light source, a cylinder surrounding the light source, said cylinder having slots therein, said slots being substantially the length of the cylinder to project a plurality of parallel beams of light onto the walls, and means to rotate the cylinder to cause the beams to travel about the walls.
- 25 12. In an amusement device the combination of a room having its inner walls covered with alternate fluorescent stripes and black stripes

spirally arranged about the walls, an ultra-violet light source, a cylinder surrounding the light source, said cylinder having longitudinal openings therein through which openings a plurality of parallel light beams are projected onto the 5 walls, and means to rotate the cylinder.

13. In an amusement device of the class described, the combination of a closure having its inner walls covered with fluorescent material, a cylindrical member, a plurality of reflecting 10 means carried by said cylindrical member, a single ultra-violet light source located axially of the cylinder, means to project light beams from said single light source simultaneously onto all of the reflecting means, the reflecting means being 15 adapted to reflect the light beams radially of the cylinder onto the inner walls of the closure.

14. In an amusement device of the class described, the combination of a closure having its inner walls covered with fluorescent material, a 20 cylindrical member, a plurality of reflecting means carried by said cylindrical member, a single ultra-violet light source located axially of the cylinder, means to project light beams from said single light source simultaneously onto all 25 of the reflecting means, the reflecting being adapted to reflect the light beams radially of the cylinder onto the inner walls of the closure, and means to rotate the cylinder.

30
